CLAIM

I claim the ornamental design for a toy, as shown and described.

DESCRIPTION

FIG. 1 is a left, front perspective view of a toy design showing my new design;

FIG. 2 is a front view of thereof;

FIG. 3 is a rear view of thereof;

FIG. 4 is a left view of thereof;

FIG. 5 is a right view of thereof;

FIG. 6 is a top view of thereof; and,

FIG. 7 is a bottom view of thereof.

The broken lines show portions of the toy that form no part of the claimed design.

1 Claim, 7 Drawing Sheets
